ZIPPER SHIRT

Morris L. Kaplan, Hazleton, Pa., assignor to The
Shirtcraft Co., Inc., Hazleton, Pa., a corpora-
tion of New York

Application April 5, 1950, Serial No. 154,097

10 Claims. (Cl. 2—128)

1

This invention relates to an improved shirt construction, and this application is a continuation-in-part of my applications, Serial Nos. 90,955, filed May 2, 1949, now Patent No. 2,639,432, dated May 26, 1953, and 110,592, filed August 16, 1949, now abandoned.

The object of the invention is to provide a shirt for general wear and which will employ a zipper fastening structure instead of the conventional buttons.

Another object of the invention is to provide a neat appearing shirt in which the zipper structure will be concealed and which may be washed and ironed without danger of having the zipper structure so emboss the front plait of the shirt as to be objectionable.

Referring to the drawings, Figure 1 is a detailed sectional view showing one step in the manufacture of the shirt wherein layers of cloth and thermoplastic impregnated cloth together with a cord are built up in superposed relation.

Figure 1A is a view similar to Figure 1 wherein in the cord is disposed between the upper or cloth layer and the thermoplastic impregnated fabric or lower layer.

Figure 2 is a sectional view showing the construction of Figure 1 or 1A attached to a shirt body, i. e., one side of the shirt front.

Figure 3 is a sectional view of the construction shown in Figure 2 after the thermoplastic layer has been fused under heat and pressure.

Figure 4 is a sectional view showing a zipper stringer attached to the construction shown in Figure 3.

Figure 5 is a sectional view showing a front plait secured to the structure shown in Figure 4.

Figure 6 is an expanded view of the construction shown in Figure 5, partly in perspective and partly in section, and showing the location of the zippers in a recess defined by the adjacent ridge formed by the inclusion of the cord.

Figure 7 is a perspective view showing the relation of the zipper stringer to the ridge formed by the cord and also showing the manner in which the stitching of the zipper stringer for securing the same may be skipped to provide an opening which will receive a tie clasp, there being any suitable number of such bridges located as desired with relation to the shirt.

Figure 8 is a view similar to Figure 7 with the parts broken away.

Figure 9 is a section on the line 9—9 of Figure 8.

Figure 10 is a sectional view similar to Figure 5 differing therefrom in that the structure

2

shown in Figures 1 or 1A through Figure 4 is attached to the front plait of the shirt as distinguished from Figure 5 wherein such structure is attached to the body of the shirt and the front plait then attached to the body.

Figures 11 to 16 show a preferred improved manner of forming a front plait which may be used in any of the forms of the invention, and

Figures 17 to 22 illustrate another manner of forming the front plait.

Referring to the drawings, in Figure 1 there is shown a layer of cotton cloth 10 and a layer of cloth 11 impregnated with thermoplastic material. These layers may be stitched together if desired along one edge as shown at 12. On one side of the layer 11 there is from one ply to a multiple amount of ply, depending on the thickness of the zipper. The cord and layers are stitched together by a central line of stitching 14, to form a strip.

In Figure 1A the cord is disposed between the layers as shown.

Either of the constructions shown in Figure 1 or 1A may be used in accordance with this invention and the inventions described in my above-mentioned copending applications.

Referring to Figure 2, the construction shown in Figure 1 or 1A is attached to the shirt body 15 forming one side of the shirt front by a line of stitching 16.

The construction shown in Figure 3 is fused under heat and pressure to flatten out the same, unite the layers 10 and 11 and the shirt body 15 by fusing and produce the longitudinally extending rib or ridge 17. As will be appreciated, the cord also will be united by fusing with the layer 11.

Referring to Figure 4, the zipper stringer 18 has the cloth portion folded upon itself and stitched as shown at 19. The line of zippers 20 is disposed in the recess defined just to the left of the ridge 17, and the zipper stringer is connected to the shirt body fabric 15 by a line of stitching 21 which may also if desired extend through the layers 10 and 11.

Referring to Figure 5, the front plait of the shirt is indicated at 22 as a whole, and comprises an inner layer of thermoplastic treated cloth 23 enclosed in a fabric layer 24. The layer 24 and the thermoplastic layer 23 are fused together and the plait so formed is stitched to the structure shown in Figure 4 by a line of stitching 25 and to the free edge portion of the shirt body 26 by a line of stitching 27. In some cases, it is desirable to fold over the free edge portion of the shirt

body as shown at 28 with the stitching 27 running through both layers of the fold, if desired. Referring to Figures 6 and 7, it will be noted that the ridge 17 forms a recess to one side thereof indicated at 29, and when the shirt is washed and ironed, the presence of the ridge 17 and recess 29 assures against any embossing of the zippers through the front plait, whereby the exposed front layer 22 of the plait is smooth and neat appearing at all times.

The fabric layer 10 and the impregnated fabric layer 11 are cut on a bias or crosswise with respect to the running length of the threads and, hence, these strips 10 and 11 shrink relatively little in the washing of the shirt. This is of considerable importance since the stringers carrying the zippers usually shrink to an appreciable extent, and since the stringers carrying the mating zippers will both shrink the same amount, the zippers will always be properly aligned which would not be the case if the layers 10 and 11 were allowed to introduce a further shrinkage factor. This, as explained is precluded by forming the strips 10 and 11 in a manner to cut the cloth crosswise or on a bias with respect to the running length of the threads.

Referring to Figure 7, the line of stitching 21 securing the stringer to the shirt body or the built up structure as shown in Figures 4 and 5 is stopped at any desired point to form a bridge 30 shown in Figure 9 for the purpose of inserting one leg 31 of a tie clasp 32 as illustrated in Figures 7 and 8. In other words, the stitching 21 is stopped to provide the spaces or bridges 30 at which the stringer is not stitched to the body or the structure shown in Figure 4 as in Figure 5, and this may be done to provide any number of bridges located at various distances below the neck of the shirt or above the waist according to the size of the garment and to meet individual tastes of the wearer.

Referring to Figure 10 and comparing the same with Figure 5, it will be noted that whereas in Figure 5 the front plait is attached to the body by lines of stitching 25 and 27, i. e., the structure shown in Figure 4 and the front plait 22 are stitched together, in Figure 10 the structure shown in Figure 4 is attached directly to the front plait which in turn is stitched to the body. The thermoplastic layer 23 is enclosed in the fabric layer 24 and the layers are fused together, with the free edge portion 33 of the fabric 24 lying open. Thereupon the structure shown in Figure 4 without the stringer 18 is stitched to the free marginal portion 33 of the fabric 24 forming the back of the shirt plait by a line of stitching 34. The stringer 18 is folded upon itself as in Figure 4 and then stitched through the layer 33 and the layers 10 and 11 by a line of stitching 35. The front section of the shirt body 15 is then stitched to the marginal portion 33 of the fabric 24 or to the folded over marginal portion 36 as shown in Figure 10 by a line of stitching 37, after which the plait portion defined by the layers 24 and 23 is folded over along the line 37' and connected to the body by a line of stitching 38. A further line of stitching 39 is provided to connect the fused layers 24-23 with the free marginal portion 33 of the fabric 24.

Referring to Figures 11 to 16, there is illustrated a preferred form of front plait which may be employed in any of the forms of this invention and in my aforementioned copending applications.

In forming this front plait, a strip of thermoplastic impregnated fabric indicated at 40 is laid upon a layer or strip of shirt fabric 41 with one marginal edge portion of the strip 40 extending beyond the marginal edge portion of the strip 41 as shown at 42 and a marginal edge of the shirt fabric 41 extending beyond the adjacent marginal edge of the strip 40 as shown at 43. Thereupon, the laminated structure is given a short fusing treatment sufficient to lightly tack the strips together to the form shown in Figures 11 and 14. The free portion 43 of the fabric is folded over the strip 40 as shown in Figures 12 and 15 at 44 and then folded again over strip 40 as shown at 45 in Figures 13 and 16. A free marginal portion 46 may or may not be present as desired. The structure shown in Figures 13 and 16 is then subjected to the usual fusing operation to form the front plait which may be sewed to the body 15 of the shirt as shown in Figures 5 and 10, as well as to the zipper structure disclosed herein. It will be observed that the strip of fabric 41 and the strip of thermoplastic treated fabric 40 are fused together throughout their coextensive areas, i. e., on both sides and ends of the fusing layer 40 including the portion 46' thereby to produce an integral strip or front plait which will retain its form and neat appearance during the life of the garment.

Referring to Figures 17 to 22, a less preferred form of front plait is illustrated which may be used in accordance with this invention and the inventions described in my aforesaid copending applications. In this form of the invention, the strip 40', i. e., the thermoplastic treated fabric, and the strip 41', i. e., the fabric facing layer for the front plait, are permanently fused together as shown at 47 in Figure 17 and Figure 20. Thereupon, the fabric strip 41' is folded at 44' about the strip 40' as shown in Figures 18 and 21, and the opposite side 43' of the fabric is not thus connected by fusing to the strip 40' so that, in the structure shown in Figures 19 and 22, the strips are only fused together at one side, namely, at the side of jointure indicated at 47 in Figure 17.

Referring to Figures 4 to 8 and Figure 10, it will be noted that the recess 29, while it may be formed only by the ridge 17 with the stringer not folded upon itself, is made more pronounced and effective to avoid embossing of the zippers upon the front of the plait during ironing or pressing, by folding the stringer 18 upon itself as shown. In other words, as shown, the recess for the zippers has two side walls defined respectively by the space between the ridge 17 and folded over stringer 18, which precludes such objectionable embossing, since both walls exert a stiffening effect and resist compression.

The disclosures of my aforesaid copending applications are hereby incorporated in and made a part of this application.

I claim:

1. A front plait for shirts comprising a relatively wide thermoplastic layer substantially enclosed in a layer of fabric, the layers being united by fusing said thermoplastic layer, a strip of thermoplastic treated fabric having fused thereto another strip of fabric, said strips being relatively narrow with respect to the width of the layers of the front plait and connected thereto on the inner side of the plait, a ridge on said narrower strips, and a stringer on the inner side of the plait and carrying zippers, said stringer being folded upon itself and connected to the front plait on the inner side thereof, the zippers

being disposed adjacent one side of said ridge whereby the latter forms a recess for the zippers, which will prevent embossing of the zippers upon the exposed surface of the plait when the latter is pressed or ironed.

2. A front plait according to claim 1 wherein said ridge is provided by a cord.

3. A front plait according to claim 1 wherein said ridge is provided by a cord disposed on the outside of said strips.

4. A front plait according to claim 1 wherein said ridge is formed by a cord attached to the outside of the thermoplastic strip.

5. A front plait according to claim 1 wherein said ridge is formed by a cord disposed between 15 said strips.

6. A shirt structure having a front plait according to claim 1 wherein said strips and stringer are connected to the body of the shirt upon opposite sides thereof.

7. A shirt structure having a front plait according to claim 1 wherein the plait is directly connected to the body of the shirt and said strips and said stringer are connected to the fabric layer on opposite sides thereof.

8. A front plait according to claim 1 wherein

said fabric strips are cut crosswise of the running length of the threads of the fabric.

9. A front plait for shirts according to claim 1 wherein said layers are fused together substantially throughout their coextensive areas.

10. A front plait for shirts according to claim 1 wherein said layers are united by fusing on one side only.
